Inventor,
Daniel M. Winans
By G. H. Anderson
his Atty.

UNITED STATES PATENT OFFICE.

DANIEL M. WINANS, OF BINGHAMTON, NEW YORK.

CURTAIN LIGHT.

Application filed October 5, 1921. Serial No. 505,537.

To all whom it may concern:

Be it known that I, DANIEL M. WINANS, a citizen of the United States, residing at Binghamton, in the county of Broome and State of New York, have invented certain new and useful Improvements in Curtain Lights, of which the following is a specification.

This invention relates to "lights" for vehicle curtains, being particularly adapted for use where a large curtain light is desired and where the vehicle top has a lining, although it is not thus limited as the invention may be embodied in a light of any size and shape and regardless of the presence or absence of the lining for the vehicle top.

The common practice heretofore where a large light is used has been to provide a wooden frame which is composed of several pieces glued together. The joints of such a frame are liable to spring apart under the strain put upon the fabric and webbing of the vehicle top in order to hold the vehicle top taut, as is commonly done. Where a wooden frame is employed the fabric is held by tacking it to the inside or seat for the glass and if it is not perfectly smooth, it becomes necessary to remove the tacks and readjust the fabric to loosen it or pull it taut and then re-tack it. The glass coming against the heads of the tacks is liable to become cracked and, further, a very uneven and insecure seat is provided for the glass, allowing water to have access to the space between the glass and the frame, resulting in discoloring the lining of the curtain, rotting the fabric, and impairing the glued joints. Wooden frames also possess the disadvantage of being difficult to suspend from points half way between the outer and inner fabric by the stay straps commonly used for that purpose, and, consequently, the outline of the stay straps shows through the lining, particularly after the fabric has become stretched.

My invention has for its object the provision of a curtain light which overcomes all of the defects inhering in curtain lights having wooden frames and which will be water tight, non-warping, will seat the glass in such manner that it is firmly held and yet is thoroughly cushioned, and which, also, renders the operation of installation rapid and easily accomplished.

In my curtain light sheet metal stampings comprise the frame and at least one of these

stampings is provided with a channel in which is a cushion packing which forms the seat that bears against the edge of the glass and said cushion is compressed when the inner and outer frames are fastened together.

Preferably rubber tubing of any desired cross sectional shape but usually circular in cross section, is employed as the packing or cushion and that form is illustrated in the drawings. It is within the scope of my invention, however, to employ an elastic cushion or packing which is solid, instead of tubular. In any instance, the cross sectional shape of the packing or elastic cushion is not essential and my invention is not limited thereto except where specifically stated in the claims.

Where the invention is used on tops having a lining, the light is preferably provided with inner and outer frames both of which have channels containing elastic or cushioning packing and, preferably, the frames are duplicates. Where the light is used on a top having no lining, the elastic packing may be employed on both the inner and outer frames, or, only on the outer frame.

The provision of duplicate inner and outer frames enables the same form of metal stamping to be employed and the same size and shape of elastic packing or cushioning to be used, beside providing for a cushion seat for both sides of the glass at its marginal portion. It is to be understood, however, that unless recited in the claims the invention is not limited to duplicate inner and outer frames, although the fact that my duplicate frames may be made up from a single set of dies serves to materially reduce their production cost. In offering the trade a stock line of modern curtain light frames, a considerable number of different sizes must be provided for in order to properly meet the expected market demands. This involves keeping on hand a corresponding large number of expensive dies for which the die charge naturally amounts to a considerable proportion of the total cost of producing stamped curtain light frames. It is a primary object of the present invention to simplify the required dies and at the same time to cut in half the die charge over such conventional types of two part frames which can not be manufactured as duplicates of each other.

To adequately stiffen the frames, they are provided with flanges which are detachably connected by any suitable fastenings, such

as screws, screw bolts with nuts, clinching connectors, and the like, permitting separation when it is necessary to replace the glass with another pane.

5 The flanges of the frames are provided with slots for the connection of the ends of the stay straps commonly used between the lining and curtain. The flanges being located midway the inner and outer frames when the 10 latter are connected together, I thus provide for the location of the stay straps midway between the lining and curtain and, consequently, when the fabric becomes stretched from use, there is little tendency for the 15 outline of the straps to show against the fabric to detract from the appearance thereof.

My invention has the advantage, among 20 others, of affording a very tight and neat connection between the fabric and the frame. Where a lining is used, the inner and outer frames are completely concealed and the curtain and fabric come to the outer and inner faces of the glass in a smooth and finished 25 manner. At the same time, the fastenings which connect the inner and outer frames together not only press the elastic cushion packing tight against the pane but the packing, being wedged into the channels in 30 the frames, tightly presses the edges of the fabric against the walls of the channels, resulting in a secure clamping action which prevents the fabric from pulling out. The frames are easily taken apart, however, when 35 the lining is unfastened from the bow of the top and, once the pressure is removed from the packing, it can be easily removed from its channel to provide for any desired adjustment of the fabric or replacement 40 thereof or of the packing. The cushion joint provided adapts itself to any unevenness in the glass and makes a water-tight joint, overcoming defects inhering in wooden frames as previously described.

45 The form of the inner and outer frames is such, regardless of whether these frames are duplicates, that they collectively form an abutment adapted to center the edge of the glass and prevent it from sliding.

50 The frames are conveniently made in the form of metal stampings of suitable gauge, affording lightness and strength. The channels constitute the interior of beads or trough-like parts of the frames. If desired, 55 particularly at rounded or angular parts of the light, the fabric of the curtain and lining may be notched or slit and held down in the channel or bead by an adhesive such as shellac.

60 I am aware that my invention is susceptible of modification without departing from its essential principle and, consequently, the disclosure of certain embodiments thereof which show preferred forms 65 are to be considered as illustrative, instead

of restrictive, of the scope of the invention.

In the accompanying drawings:

Figure 1 is a view looking toward the outside of an automobile curtain which is equipped with my improved frames and 70 light, the curtain being broken away and the lining and stay straps appearing in full lines.

Fig. 2 is a detail perspective view partly in cross section and with certain parts 75 broken away, looking toward the light from the inside of the curtain.

Fig. 3 is a detail view looking toward the inner face of the outer frame at the curved corner, showing the manner in which the 80 margin of the curtain may be slit and also illustrating how the elastic packing is applied.

Fig. 4 is a detail section of a modification where the elastic cushion is used on only 85 one side of the glass; and

Fig. 5 is a detail of another modification showing channels or beads of polygonal form.

The curtain appears at 1 and the lining is 90 shown at 2. The pane of glass or "light" appears at 3. The stay straps are shown at 4.

Referring first to Figs. 1 and 2, the outer metal frame 5 and inner metal frame 6 are 95 duplicate stampings, each having a bead 7 and a flange 8. The flanges 8 are provided with registering slots 9 through which the stay straps 4 are looped and held by suitable clips 10. The frames 5 and 6 are securely held together, with the flanges 8 clutting, by fastenings 11. The fastenings 11 may be of any desired form; I have shown 100 screw bolts and nuts, the latter bearing against the beads 7 which prevent them 105 from becoming accidentally unscrewed. However, screws could be substituted which will be passed through one of the flanges and engage screw threads on the other flange or, split expanded fasteners might be used. 110 Whatever fasteners are employed, the flanges 8 are clamped tightly together and located half way across the width of the frames 5 and 6 so that the stays 4 are located midway 115 the curtain 1 and lining 2 and hence do not show any outline against the fabric.

The beads 7 are of trough-shape and thus provide endless grooves or channels 12 which face the pane 3, but preferably do not touch it except where they come together at 13 120 and constitute an abutment for the edge of the pane to prevent the latter from sliding.

The margins of the curtain 1 and lining 2 are brought around the piece 7 and laid inside the channels 12, as shown at 14. Elastic 125 cushioning or packing strips 15 are pressed against the infolded margins 14 and fill the channels 12. The elastic packing strips or cushions 15 are shown as being pieces of cylindrical rubber tubing which extend all 130

the way around the channels and are of such diameter that they snugly wedge into the channels 12 and firmly hold the fabric (either 1 or 2, or both) in the beads. The 5 elastic packings 15 project from the beads and, consequently, when the frames 5 and 6 are in position as shown in Fig. 2, the packing 15 is compressed and forms a tight, yet elastic, seat for the sides of the marginal 10 portion of the pane 3 and wedge the margins of the fabrics into the channels 12, thus tightly clamping the fabrics to the frames. Preferably the beads will be so formed that where the fabrics are re-bent back into the 15 channels, they will not touch the pane.

In the modification shown in Fig. 4 the curtain 1 has no lining. The outer frame 5, its bead 7, and the elastic cushion 15 are employed but in lieu of the inner frame 6 there 20 is employed a stamped metal frame 16 having a flange 8^a to correspond with the flange 8 on the outer frame 5, the flange 8 being provided with a bent part 8^b to match the corresponding part on the flange 8^a. The 25 bent flanges 8^a, 8^b, afford a neater finish when the lining is not employed but it will be understood that the flanges may appear as in Figs. 1 and 2. The frame 16, in this modification, has no elastic packing. The frames 30 are fastened by any suitable fastenings 11.

The modification shown in Fig. 5 is in all respects similar to the construction shown in Figs. 1, 2 and 3 except that the beads 7 may be of general squared or angular or polygonal 35 form.

In all forms of the invention the beads are covered by the fabric and, with the exception of the form shown in Fig. 4, the metal frames are completely covered so that 40 no fastenings, nuts, screw heads or the like appear to mar the finished appearance of the light. Consequently the light is well adapted for use not only on tops for moderate priced automobiles but also for expensive 45 ones where particular attention is paid to having the fittings or trimmings of highly finished appearance.

In Fig. 3 the fabric 1 is shown as slit or cut, facilitating its conformation to the 50 channel at the curved or angular part of the frame.

The inturned or marginal parts of the fabric which enter the channels of the beads may be secured by shellac, if desired, particularly at corners or angles as shown in Fig. 53. It is pointed out, however, that my improved trough shaped corrugation serves a two fold purpose and that by its use in connection with a resilient packing, it becomes 58 unnecessary to resort to any spurs, prongs or cementing of the fabric to the frame member. In fact, an important advantage afforded by the described disposition of these elements lies in the ease with which each 65 frame section may be secured to its respec-

tive fabric preparatory to the final assembly of the frame structure as applied to vehicle purposes.

In the preferred method of mounting and concealing my two part frame between lined curtains, the slotted marginal edges or flaps of one of the fabric openings are first in-turned over the free inmost leg edge of its frame corrugation and smoothly fitted against the interior trough surface of the 75 grooved recess as shown in Fig. 3, whereupon the inserted resilient packing may be worked into this recess to snugly press the interposed fabric flaps against said confining surface. It will be apparent that this 80 preliminary tie or retaining means for said flaps with respect to their respective frame sections, is still such that the flaps may readily be adjusted to facilitate a perfectly 85 smooth and unwrinkled mounting of either the curtain or the lining fabric prior to mounting the complementary frame members in place upon the vehicle.

This adjustable feature is one of primary 90 importance, particularly as applied to the fully concealed type of frame, since it allows of perfect mounting at a low cost of installation.

The tubular packing is preferably of a 95 size that will more than fill the trough-shaped corrugation so as to allow a portion of the resilient packing to extend outward beyond the free inmost leg edge thereof. After each of the complementary frame sections 100 have been prepared in the fashion indicated, they are bolted together and drawn toward the pane, which in turn causes the outstanding packing portions disposed on opposite sides of the pane to be pressed more tightly against the interposed inturned fabric, without however allowing the inmost leg edge of the frame to contact the pane. This improved mounting not only securely 105 grips both the curtain and the lining fabric in place and prevents them from tearing out of their respective frames, but the packing at the same time serves to make a tight water proof seal between the curtain fabric and the pane in an eminently simple and effective manner.

It is within the scope of my invention to 110 clamp the fabric between the flanges 8, or 8 and 8^a, instead of clamping the fabric in the manner shown in the drawings and hereinbefore described. In that event, the flanges 120 would hold the fabric and the sole function of the elastic packing 15 would be to form an elastic seat or cushion for the pane for the purpose of clamping it and forming a water tight joint.

I claim:

1. A curtain light holder comprising pane-holding frames having flanges disposed face to face in close relationship around the edge of the pane, fastenings se- 130

curing said flanges together, and packing carried by either or both of the frames, and bearing on the side of the pane, and a curtain fabric held by said packing against 5 the frame and concealing the frame having the packing.

2. A curtain light holder comprising pane-holding frames having flanges disposed face to face in close relationship 10 around the edge of the pane, one or both of said frames being provided with a trough-shaped bead disposed in an overlapping relation to the margin of one face of the pane, packing carried in the bead or beads, fastenings securing said flanges together, and a curtain fabric held in said bead by said packing and concealing the bead and its frame.

3. A curtain light holder comprising 20 pane-holding frames having flanges disposed face to face in close relationship around the edge of the pane, fastenings securing said flanges together, and packing carried by either or both of the frames and bearing

25 on the side of the pane, said frames collectively being adapted to constitute an abutment surrounding the edge of the pane to prevent it from sliding, and a curtain fabric held by said packing against the frame 30 and concealing the frame having the packing.

4. A curtain light holder comprising duplicate pane holding frames having flanges disposed face to face in close relationship 35 around the edge of the pane, fastenings securing said flanges together, said frames being provided with trough-shaped beads located on opposite sides of the pane, packings in said beads which are disposed on opposite sides of the pane, and curtain fabrics whose edges are inturned and lie between the respective beads and the pane, said curtain fabrics wholly concealing both of the frames.

45 5. In a curtain light comprising a pane and complementary frame members therefor, each such frame member being provided with an outstanding sheet metal flange for one of said members adapted to encompass 50 and center the edge of the pane and disposed to lie within the planes defining the sides of said pane, and an integral cross-sectionally trough-shaped corrugation of which one trough leg extends laterally from the centering edge of said flange while the other somewhat shorter leg thereof is inwardly disposed in an overlapping relation to the margin of one side face of the pane, a resilient packing inserted in said corrugation, a 55 curtain fabric interposed between said corrugation and the pane, means carried by the other frame member adapted to engage the opposite side of the pane, and fastening means adapted to clamp the flanges about 60 the pane.

6. In a curtain light comprising a pane and complementary frame members therefor, each such frame member being provided with an outstanding sheet metal flange for one of said members adapted to encompass 70 and center the edge of the pane, and an integral cross-sectionally trough-shaped corrugation of which one trough leg extends laterally from the centering edge of said flange while the other leg thereof is inwardly disposed in an overlapping relation to the margin of one side face of the pane, a resilient packing inserted in said corrugation, a curtain fabric disposed in an offset relation to the packed side of the pane, said curtain having an opening of which the inner border portion is inturned over the free inmost leg edge of said corrugation, means carried by the other frame member adapted 75 to engage the opposite side of the pane, and clamping means between said complementary members serving to hold said packing in sealed engagement with the inturned fabric border.

7. In a curtain light comprising a set of 90 duplicate sheet-metal frame members adapted to clamp a pane therebetween, each such frame member being provided with an outstanding flange encompassing and centering the edge of the pane and adapted to abut face 95 to face around the edge of the pane, a cross-sectionally trough-shaped corrugation being provided for each of said flanges of which corrugation one trough leg extends laterally and away from the plane of the pane while the other leg of said trough is disposed inwardly in relation to the aforesaid leg and toward the pane, an inserted packing for each of said corrugations disposed on opposite sides of the pane, a curtain fabric having an opening therethrough of which the inner border portion is inturned over the free inmost leg edge of one of said corrugations, and fastening means 100 for the abutting flanges serving to clamp both packings toward the pane and simultaneously make a weather proof joint between said inturned fabric and the pane.

8. In a curtain light comprising a set of 115 duplicate sheet metal frame members adapted to clamp a pane therebetween, each such frame member being provided with an outstanding flange encompassing and centering the edge of the pane and adapted to abut face to face around the edge of the pane, the inner centering edge of the respective flanges being extended laterally and away from their abutting flange faces, each terminating in an integral cross-sectionally trough-shaped corrugation one of whose trough legs extends laterally and away from the plane of the pane while the other leg of said trough is disposed inwardly in relation to the aforesaid leg and toward the pane, an inserted packing seated in each of said cor- 120 125 130

- rugations and disposed on opposite sides of the pane, a curtain fabric having an opening therethrough of which the inner marginal portion is inturned over said inmost edge 5 of one of the corrugations to conceal said corrugation and to make a weatherproof joint with the pane, and clamping means adapted to draw said duplicate members toward the pane.
10. 9. In a curtain light comprising members adapted to clamp a pane therebetween, each such frame member being provided with an outstanding flange for one of said members mounted around the edge of the pane, a 15 cross-sectionally trough-like corrugation being provided for said flange, of which corrugation one trough leg extends laterally and away from the flange and the plane of the pane while the other leg thereof is disposed inwardly in relation to the aforesaid leg and toward the pane, an inserted packing for said corrugation, and a curtain fabric having an opening therethrough of which the inner border portion is inturned 20 over the free inmost leg edge and between said corrugation and the packed side of the frame, the curtain proper being disposed outwardly and away from said free leg edge in an offset relation to the packed side of the 25 pane.
30. 10. In a curtain light comprising frame members adapted to clamp a pane therebetween, a flange element for one of said members mounted around the edge of the pane, a cross-sectionally trough-like corrugation being provided for said flange adapted to overlap the margin of one face of the frame, an inserted packing for said corrugation, said packing adapted to more than fill said 35 trough and resiliently bear against the surface defining the interior of said trough, and a curtain fabric having an opening therethrough of which the inner marginal portion is inturned over the free inmost leg 40 edge of said corrugation and interposed between said packing and the interior trough surface to constitute a preliminary adjustable tie therebetween adapted to facilitate the unwrinkled mounting of the inturned 45 curtain fabric with respect to said frame member.
50. 11. In a curtain light comprising a set of duplicate endless frame members adapted to be clamped about a pane, each such member being provided with a flange encompassing 55 the edge of the pane and with a cross-sectionally trough-shaped corrugation for each of said flanges, said corrugations being disposed inwardly of their respective flanges and in an overlapping relation to the margin 60 portion of opposite sides of the pane, an inserted packing for each of said corrugations adapted to more than fill and resiliently bear against the surface defining the interior of said trough, a curtain fabric having an opening 65 therethrough for each of said members, of which fabrics the inner border portion is inturned over the free inmost edge of its respective corrugation and interposed between its packing and the respective interior trough surface to constitute a preliminary adjustable tie with respect to the corresponding frame member, and clamping means for 70 said flanges adapted to draw both packings toward the pane and serving to augment the adjusted grip of said packings upon their respective interposed inturned fabrics, said curtain fabrics being spaced apart and blinded in to wholly conceal both frame members and also their clamping means.
75. 12. In a curtain light comprising frame members adapted to clamp a pane therebetween, a flange element for one of said members mounted around the edge of the pane, a cross-sectionally trough-like corrugation being provided for said flange adapted to overlap the margin of one face of the pane, a resilient packing inserted within said corrugation adapted to grippingly engage the 80 interior sides thereof, a curtain fabric having an opening therethrough of which the inner marginal portion is inturned and interposed between a gripped side of the corrugation and its packing, said inserted packing constituting a preliminary adjustable holding means for said inturned fabric, means carried by the other frame member adapted to engage the opposite side of the pane, and clamping means between said 85 members adapted to draw said packing toward the pane and serving to augment the adjusted grip of said packing upon said interposed inturned fabric.

In testimony whereof I affix my signature.

DANIEL M. WINANS.
